UNITED STATES PATENT OFFICE

WILLIAM S. HAMM AND HARRY D. SEVISON, OF ELKHART, INDIANA, ASSIGNEES TO
THE ADLAKE COMPANY, OF CHICAGO, ILLINOIS, A CORPORATION OF ILLINOIS

SASH GUIDE

Application filed July 30, 1931. Serial No. 553,912.

- One of the principal objects of this invention is to provide an improved sash guide which will effectively seal an associated sash against the entrance of water, cinders, dust and air, and will also prevent water and other foreign matter, even if present in large quantities, from accumulating and backing up in the lower portion of the guide against the sealing means.
- 10 Another important object of the invention is to provide an improved sash guide which permits easy removal of the sash, allows the sash to be moved up and down with very little effort, and is quite attractive in appearance.
- 15 The sash guide of the invention, while capable of rather general use, is of particularly great value in its application to the windows of railway cars, motor buses, airplanes, 20 and other passenger vehicles which move at high speeds, as such windows are continually being subjected to hard horizontally driving currents of air containing water, cinders, dust and other foreign matter.
- 25 Other more specific objects and advantages of the invention will be apparent to those skilled in the art upon a full understanding of the construction, arrangement and operation of the improved sash guide.
- 30 In order that the invention may be readily understood, two slightly different structural forms of the same are presented herein, but it will of course be appreciated that such forms are primarily intended for the purpose 35 of illustration and that the invention is capable of embodiment in various other forms coming equally within the scope of the appended claims.
- 40 In the accompanying drawings:
- Fig. 1 is a fragmentary outside face view of a railway car window equipped with the improved sash guide;
- Fig. 2 is a horizontal section through one side of the window, taken on the line 2—2 of Fig. 1;
- Fig. 3 is a vertical section through the bottom of the window, taken on the line 3—3 of Fig. 1;
- 50 Fig. 4 is an outside face view of a removable sash-retaining strip which forms a part of the guide;
- Fig. 5 is an edge view of the strip;
- Fig. 6 is an inside face view of the strip;
- Fig. 7 is a vertical section through the strip, taken on the line 7—7 of Fig. 4;
- Fig. 8 is a horizontal section through the strip, taken on the line 8—8 of Fig. 4;
- Fig. 9 is a fragmentary outside face view of a single sash window embodying a slightly modified form of the invention;
- Fig. 10 is a horizontal section through one side of the window, taken on the line 10—10 of Fig. 9;
- Fig. 11 is a vertical section through the bottom of the window, taken on the line 11—11 of Fig. 9; and
- Fig. 12 is an outside face view of the guide shown in Figs. 9 to 11 inclusive.
- The railway car window shown in Figs. 1 to 8 inclusive of the drawings is of the double sash type, but the invention is equally applicable to windows of the single sash type, which latter type is used quite extensively in motor buses and in railway cars engaged in suburban service.
- The particular window shown in those views consists of an outside sash 10 and an inside sash 11, which sashes are positioned in a window opening 12 and are slidably mounted in two double guides at the sides of the opening. The guides are the same at both sides of the opening, wherefore only the guide 13 at the left side need be described.
- The guide 13 includes a sheet metal strip 14 (see Fig. 2) which is attached by screws, bolts or other suitable means, to the post plate at the side of the window opening. The portions of the guide which engage with the outer and inner sashes 10 and 11 are separated from each other by a center rib 15 which is formed in the strip 14. If the guide is used for only one sash instead of two, the strip 14 may be terminated at the location of the rib 15 and only the outer portion of the strip 14 employed.
- The outer portion of the strip 14 is positioned in opposition to the edge of the side rail 16 of the outer sash, and is provided with an outer groove 17, an inner groove 18,

a connecting web 19 between the grooves, and a side wall 20 which projects beyond the web 19 flush with the inner side of the inner groove 18.

10 The inner groove 18 contains a thin, flexible spring strip 21 which projects from the groove in outwardly bent converging relation to the inner face of the side rail 16 of the sash. The free edge of the strip 21 bears resiliently against the inner face of the side rail 16 at 22 in line contact with the latter.

15 The outer groove 17 contains a removable sash-retaining strip 23. The portion 24 of the strip 23 which is positioned in the groove 17 is flat, while the portion 25 of the strip which projects from the groove is of outwardly convex channel formation, resulting in a groove 26 in the inner face of the strip in slightly spaced opposition to the outer 20 face of the side rail 16. The groove 26 in the strip contains a thin, flexible spring strip 27 which converges toward the outer face of the side rail 16 and engages resiliently at 28 in line contact with the latter.

25 The portion 24 of the strip 23 may be provided with several bayonet slots 29 for interlocking engagement with rivets, screws or other suitable members positioned cross-wise in the groove 17, or any other suitable 30 means of attachment may be employed. To remove the sash 10, it is merely necessary to shift the strip 23 upwardly a little in the groove 17, whereupon it may be moved laterally out of the groove.

35 The sash 10 is thus supported resiliently between the thin, flexible spring strips 21 and 27, in line contact only with such strips, with the side wall 20 limiting the extent of inward movement of the sash and with the outer edge 40 of the channel-shaped portion of the strip 23 limiting the outward movement of the sash. This construction permits the sash to be moved up or down very easily with a minimum of friction, and also affords an efficient 45 seal along the contact lines 22 and 28.

The outwardly convex channel portion 25 of the strip 23 is provided, near the lower end thereof, with several downwardly and outwardly opening louvers 30 for carrying away 50 the water, cinders and other foreign matter which passes the edge of the strip and enters the groove 26. The louvers 30, by affording free drainage for the water and other foreign 55 matter in the groove 26, prevent the same from accumulating and building up inside of the groove along the sealing line 28.

The water which runs down the outer face 60 of the strip 23 from the louvers 30 is deflected outwardly away from the lower end of the strip by a curved lip 31 at the bottom of the strip, which lip is preferably coextensive in width not only with the channel portion 25 of the strip but with the inner attaching portion 65 24 as well and is spaced only far enough

away from the latter to accommodate the adjacent flange 32 of the strip 14.

The water and other foreign matter is prevented from reaching the lower end of the groove 26, and also from entering the bottom 70 of the groove from below, by a vertically elongated plug 33 of triangular cross section, which plug substantially fills the space in the lower portion of the groove between the base of the groove and the outer surface of the spring strip 27 but is so proportioned as to not interfere with the action of the latter. The plug 33 extends upwardly a little past the bottom of the lowermost louver 30, and is beveled off at the top to direct the descending 80 water and other foreign matter toward the louver.

The draining and deflecting arrangement above described does not detract at all from the appearance of the guide and serves very 85 effectively to prevent leakage of water and other foreign matter past the outer sealing portion of the guide even when the latter is practically deluged with water. When air currents impinge against the spring strip 27, 90 the converging relation of the same with respect to the outer face of the side rail 16 serves to make the strip hug the rail even more snugly, thereby increasing the effectiveness 95 of the seal afforded by the strip. While this improvement has been described in its application to an outer guide portion which is detachable, it will of course be understood that it is also applicable to an outer guide portion 100 which is not detachable, since it is frequently found desirable to so construct the guide as to permit removal of the sash from the inside 105 of the bus or car.

Such an arrangement is shown in Figs. 9 to 12 inclusive. In those views, the improvement which constitutes the invention is embodied in a guide 34 of the single sash type, which guide has a fixed outer wall 35 and a removable inner wall 36. The outer wall 35 overlies a thin flexible spring strip 37 which is seated in a groove 38 in the back of the guide. The spring strip 37 is of less width than the outer wall 35 and projects from the groove 38 into line contact engagement with the outer face of the side rail 39 of the sash 11: at 40.

The outer wall 35 of the guide is provided, in the lower end thereof, with a plurality of downwardly and outwardly opening louvers 41, which are intended to function in the same 120 way as the previously described louvers 30, and the outer wall is also provided, beneath the louvers, with a downwardly and outwardly extending deflecting lip 42, which is intended to function in the same way as the 125 lip 31. The space between the outer wall 35 and the outer face of the side rail 39, beneath the lowermost louver 41, is preferably occupied by a filler member 43 which, like the previously described block 33, serves to shunt 130

the foreign matter through the louvers without interfering with the lower end of the spring sealing strip 37. The edge 44 of the outer wall is shown as substantially straight, 5 instead of being turned toward the outer face of the side rail, but it may of course be turned in if desired.

We claim:

1. In a sash guide, a thin flexible spring 10 strip adapted to engage resiliently with the outer face of a vertically slideable sash, a rigid protective strip in front of the spring strip, and a vertically arranged series of downwardly discharging louvers in the rigid 15 strip adjacent the lower end of the latter for draining the space between the rigid strip and the spring strip.
2. In a sash guide, a thin flexible spring 20 strip adapted to engage resiliently with the outer face of a vertically slideable sash in angularly disposed line contact with the same, a protective strip in front of the spring strip, and means adjacent the lower end of the protective strip for draining the space between 25 the latter and the spring strip.
3. In a sash guide, a thin flexible spring 30 strip adapted to engage resiliently with the outer face of a vertically slideable sash, a rigid protective strip in front of the spring strip, means for draining the space between the rigid strip and the spring strip, and means for deflecting the drainage outwardly away from the bottom of the rigid strip.
4. In a sash guide, a thin flexible spring 35 strip adapted to engage resiliently with the outer face of a sash, a rigid protective strip in front of the spring strip in spaced relation to the free edge of the latter, means for closing off the lower portion of the space between 40 the rigid strip and the spring strip, means for draining the space above said last mentioned means, and means for deflecting the drainage outwardly away from the bottom of the rigid strip.
5. In a sash guide, a thin flexible spring 45 strip adapted to engage resiliently with the outer face of a sash, a rigid protective strip in front of the spring strip in slightly spaced relation to the free edge of the latter, a filler 50 member attached to the rigid strip in the lower portion of the space between the latter and the spring strip, louvers in the rigid strip above the filler member for draining the space above the latter, and a downwardly and outwardly inclined lip on the lower end of the rigid strip beneath the louvers for deflecting the drainage outwardly away from the bottom of the rigid strip.
6. In window construction, in combination, 60 a vertically slideable sash, two thin flexible spring strips in resilient line contact with the outer and inner faces of the sash for guiding the latter, two members for protecting the spring strips and limiting the outward and inward movement of the sash, and means for

preventing the accumulation of water in the space between the lower portions of the outer member and the outer spring strip.

7. In a sash guide, a fixed strip, a removable strip connected with the fixed strip, a thin flexible spring strip secured to the removable strip for resilient engagement with the sash in the guide, and means adjacent the bottom of the removable strip for preventing water from accumulating in the space between the removable strip and the spring strip. 70

8. In a guide for a vertically slideable sash, an outside stop for the sash, and an outwardly projecting lip adjacent the lower end of the stop for deflecting water away from such end. 75

9. In a guide for a vertically slideable sash, an outside stop for the sash, and a downwardly and outwardly inclined lip adjacent the lower end of the stop for shielding such end. 80

10. In a sash guide, a thin flexible spring strip adapted to engage resiliently with the outer face of a vertically slideable sash, a protective strip in front of the spring strip, said strips being so arranged as to leave a laterally open space therebetween, and means for outwardly venting the laterally open space present between the protective strip and the spring strip. 85

11. In a sash guide, a thin flexible spring strip adapted to engage resiliently with the outer face of a vertically slideable sash, a protective strip in front of the spring strip in spaced relation to the free edge of the latter, means for substantially closing off the lower portion of the space between the protective strip and the spring strip, and means in the protective strip for draining the space above said last mentioned means. 90

12. In a sash guide, a thin flexible spring strip adapted to engage resiliently with the outer face of a vertically slideable sash, a protective strip in front of the spring strip in spaced relation to the free edge of the latter, means for substantially closing off the lower portion of the space between the protective strip and the spring strip, means in the protective strip for draining the space above said last mentioned means, and means for deflecting the drainage outwardly away from the bottom of the protective strip. 105

13. In a sash guide, a thin flexible spring strip adapted to engage resiliently with the outer face of a sash, a rigid protective strip in front of the spring strip in slightly spaced relation to the free edge of the latter, a filler member attached to the rigid strip in the lower portion of the space between the latter and the spring strip, one or more louvers in the rigid strip above the filler member for draining the space above the latter, and a downwardly and outwardly inclined lip adjacent the lower end of the rigid strip beneath the louvers for deflecting the drainage 110

120

125

130

outwardly away from the bottom of the rigid strip.

14. In window construction for rapidly moving vehicles, in combination, a vertically slidable sash, two thin flexible spring strips in resilient line contact with the outer and inner faces of the sash for guiding the latter, two members in slightly spaced relation to the sash for protecting the spring strips and

10

limiting the outward and inward movements of the sash, and means for preventing the accumulation of water which might otherwise become pocketed by air pressure in the laterally open space present between the lower portions of the outer member and the outer spring strip.
